UNITED STATES PATENT OFFICE.

HOOPER B. STRAUT, OF CULBERTSON, NEBRASKA.

CALF-WEANER.

SPECIFICATION forming part of Letters Patent No. 297,870, dated April 29, 1884.

Application filed February 14, 1884. (No model.)

To all whom it may concern:

Be it known that I, HOOPER B. STRAUT, a citizen of the United States of America, residing at Culbertson, in the county of Hitchcock and State of Nebraska, have invented 5 a certain new and useful Improvement in Calf-Weaners; and I do hereby declare the following to be a full, clear, and exact description of the invention, such as will enable others skilled in the art to which it appertains to 10 make and use the same, reference being had to the accompanying drawings, and to letters or figures of reference marked thereon, which form a part of this specification.

15 My invention relates to calf-weaners; and it consists in the improvements hereinafter described and set forth.

In the accompanying drawings, Figure 1 is 20 a perspective view, illustrating my improvement and its application; and Fig. 2 is a detail perspective.

The weaner consists of a plate, A, which is 25 preferably formed from a blank of sheet or other metal. One portion of said plate is cut so as to form the side extensions, *a a*, and is notched to form a series of teeth, *b*. The extensions *a a* are bent over and secured by rivets *c*, so as to form loops for the passage of a metallic rod, B. The teeth *b* are bent up at 30 right angles from the plate A, as shown.

In applying the device, the tip of the nose of the animal is caused to occupy the space between the extensions *a a*, so that the pointed rod B can be forced through the said tip 35 and bent at either side to form shoulders *d*, which retain the said plate in position. The

metallic rod B is preferably bent at one side before it is caused to pierce the animal's nose, this arrangement permitting a hold to be secured on the same in forcing it through the nose. By bending the rod B as described the pointed ends of the same occupy a position at the sides of the nose, and serve as an additional means for weaning. The teeth *b*, being in a vertical position, will prick the udder of the cow when the nose of the calf approaches the same.

From the foregoing it will be apparent that the device herein described is of simple and inexpensive construction, of ready application, and effective in operation.

I claim—

1. As an improved article of manufacture, a calf-weaner consisting of a plate having integral teeth arranged as described, and extensions at each side of said teeth bent to form loops for the purpose set forth, and securing-rod pointed at its ends and bent near one end, substantially as specified.

2. As an improved article of manufacture, 6 a calf-weaner consisting of a plate having integral teeth arranged as described, and extensions at each side of said teeth bent to form loops for the passage of a securing-rod, and a rod pointed and bent at each end when in position, substantially as specified.

In testimony whereof I affix my signature in presence of two witnesses.

HOOPER B. STRAUT.
